(57) CLAIM

The ornamental design for a chair as shown and described.

DESCRIPTION

FIG. 1 is a front, left, and top perspective view of a chair, showing my new design;

FIG. 2 is a rear, right, and bottom elevation view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of an encircled area labeled “9” in FIG. 1.

The dot-dash broken lines shown in FIGS. 1 and 9 framing portions of the chair for enlargements purposes form no part of the claimed design.

1 Claim, 9 Drawing Sheets
